UNITED STATES PATENT OFFICE.

ELMER A. REID, OF TRENTON, NEW JERSEY, ASSIGNOR TO AJAX RUBBER COMPANY, INC., OF MILLBROOK, NEW YORK, A CORPORATION OF NEW YORK.

DESIGN FOR A TIRE-CASING.

53,750.

Specification for Design.

Patented Aug. 26, 1919.

Application filed May 13, 1919. Serial No. 296,942. Term of patent 7 years.

To all whom it may concern:

Be it known that I, ELMER A. REID, a subject of the King of Great Britain, and resident of Trenton, in the county of Mercer and State of New Jersey, have invented a new, original, and ornamental Design for a Tire-Casing, of which the following is a specification, reference being had to the accompanying drawing, forming part thereof.

My new design for a tire casing is shown in the accompanying drawing, in which—

Figure 1 represents a plan view of a portion of a tire casing.

Fig. 2 represents a transverse section of the same, and

Fig. 3 represents a side elevation of the same.

I claim:

The ornamental design for a tire casing substantially as shown.

ELMER A. REID.
